Patented Aug. 8, 1972

224,584

LACING HOOK

Danilo Parpaila and Giancarlo Callegaro, both of
Via Cesare da Sesto 15, Milan, Italy

Filed Apr. 30, 1971, Ser. No. 110,356

Term of patent 7 years

Int. Cl. D2—07

U.S. Cl. D2—418

Fig. 1

Fig. 2

Fig. 3

FIG. 1 is a front elevational view of a lacing hook showing our new design;

FIG. 2 is a side elevational view taken from the left in FIG. 1; and

FIG. 3 is a rear elevational view.

We claim:

The ornamental design for a lacing hook, substantially as shown.
